[57] ABSTRACT

A child's toy which includes supporting structure for simulated bodies resembling animals, autos, aeroplanes and the like which may either be provided with seats extending between opposite simulated sides of the body, or a saddle upon the back of a simulated horse or pony, the body being supported by spring means which will permit tilting, swivelling or pivoting vertical bouncing movement. To further enhance the potential movement of the simulated body, one or more of the same are supported upon a platform suspended between a pair of transversely spaced upright members by means of elongated members extending downwardly from the upper portions of said upright members for purposes of additionally providing swinging or gliding movement of said platform and simulated body thereon back and forth, substantially within horizontal planes to obtain linear travel as well as a rock and swivel bounce in a vertical plane, perpendicular to the horizontal. Power means are also provided to effect such swinging movement of said platform and the animal body, if desired.

**RIDING RECREATIONAL TOY
SPRING-MOUNTED ON A SWINGING PLATFORM**

BACKGROUND OF THE INVENTION

For many years, so-called hobby horses have been in existence which are composed of a body simulating a horse, usually with feet extending outwardly from opposite ends of the body, downwardly extending pivoted members engaging the feet to provide a to and fro movement of the horse. Similarly, over the years, there have been a number of developments in the field of spring-mounted horses to provide toys upon which children could be positioned to simulate a rider, the springs providing somewhat of a tilting, or vertical up and down movement, on coil type extension springs with no attempt to provide a back and forth linear horizontal movement. Examples of the latter type of horse-simulating toys are found in the following U.S. Pat. Nos.:

- 1,289,382 — Brurock — 1918
- 2,746,754 — Martel — 1956
- 2,756,051 — Shone — 1956
- 2,769,484 — Kairath — 1956
- 2,953,375 — Horgan — 1960

It will be seen that none of the foregoing patents disclose a toy comprising a simulated animal or other riding type toy in which there is provided both vertical up and down, tilting movement, as well as back and forth linear movement substantial within a horizontal plane. It is the general purpose of the present invention to provide such combination movements in a toy which offers safe riding amusement, particularly one in which more than one child simultaneously can occupy the simulated bodies of a riding nature.

SUMMARY OF THE INVENTION

It is the principal object of the present invention to provide a riding type toy for children comprising a platform, at least one simulated body having seat means thereon, spring means extending between said platform and said body for purposes of permitting vertical oscillating and pivotal spring or bouncing movement of the body, perpendicular to the platform, a frame having a pair of transversely spaced upright members respectively adjacent opposite side edges of said platform, elongated suspending members extending downward from the upper portions of said upright members and arranged for swinging movement of the lower portions thereof relative to the pivotally supported upper end portions, and means interconnecting the lower portions of the suspended members to the platform at transversely spaced locations to provide support for the platform and the one or more bodies thereon and also permit swinging movement thereof back and forth in opposite substantially horizontal directions to provide a compound movement of said animal body under controlled conditions to provide adequate safety and freedom from injury to children mounted upon the simulated animal body, or other bodies.

For purposes of the invention, it is contemplated that the body for the riding type toy may comprise a simulated animal such as a horse or pony, automobile, airplane, or a number of other riding type vehicles or objects. To simplify the illustration and description of the invention herein several types of toy horses have been selected for specific illustration and these are to be

considered representative of the above described group.

It is another object of the invention to provide pairs of elongated members adjacent each upright member, 5 at transversely spaced locations, to provide substantially horizontal movement of the platform, at various elevations controlled by the pivotal movement of said suspending members.

It is a further object of the invention to provide a plurality of spring means respectively adjacent opposite sides of an animal body, the same being connected to said platform and engaging said animal body substantially adjacent opposite ends thereof to afford limited tilting, pivoting or swivelling movement of said body 15 relative to the platform in connection with said vertical movement of the animal body.

Still another object of the invention is to provide said spring means in the nature of oppositely bowed portions, the upper portions thereof being secured to

20 transverse members extending through said animal simulating body, substantially adjacent opposite ends thereof, said transverse members being fixed non-rotatably relative to the animal body and projecting from opposite sides of the body for connection to said upper portions of said spring means.

It is a further object of the invention to provide substantially stiff means extending between and connected to the outwardly extending ends of said transverse members connected to said animal simulating body for purposes of preventing relative rotation between said transverse members and said body.

Still another object of the invention is to provide a foot rest bar projecting transversely through the forward portion of said simulated animal body or other type of body contemplated by this invention, said bar normally being spaced above said spring means but adapted to engage said spring means when said body tilts downwardly at the forward end a predetermined amount and thereby restricts such downward tilting movement to provide safety and prevent accident to a child riding said body.

One further object of the invention is to provide various arrangements of generally S-shaped spring means having portions facing each other in opposite directions and adapted to provide limited vertical bouncing movement of the simulated animal body relative to the support and platform.

It is still another object of the invention to provide an intermediate supporting frame between the lower portions of said elongated members and said platform and provide motor means beneath said platform and a rocking arm driven by said motor and engaging said platform to move it limited amounts horizontally for swinging to and fro.

Ancillary to the foregoing object, it is a further object to provide said platform with an upstanding member at one end and pin and slot co-engaging means between said upstanding member and said rocking arm to effect driving movement between said arm and member.

One further object of the invention is to provide quick detachable positioning and securing means between said platform and said intermediate supporting frame preferably in the form of angular pins adjacent one edge of said supporting frame and bolts having wing nuts thereon adjacent the opposite edge, whereby said platform and the animal simulating bodies connected thereto may be removed from said intermediate

supporting frame and disposed upon a supporting surface such as a floor when simple bouncing movement is required in the absence of horizontal swinging movement.

Details of the foregoing objects and of the invention, as well as other objects thereof, are set forth in the following specification and illustrated in the accompanying drawings comprising a part thereof.

BRIEF DESCRIPTION OF THE DRAWINGS

FIG. 1 is an exemplary front vertical elevation of a riding toy specifically shown as a toy horse as representative of a substantial group of riding type toys and embodying the principles of the present invention and illustrating two different types of animal-simulating bodies supported upon an intermediate frame.

FIG. 2 is a fragmentary end view of the toy shown in FIG. 1 as seen on the line 2-2 of FIG. 1.

FIG. 3 is a vertical section of an elevation of one of the animal-simulating bodies and the supporting means therefore shown in FIG. 1 as seen on the line 3-3 of said figure.

FIGS. 4 and 5 respectively show different arrangements of spring-supporting means for the animal-simulating bodies of the type shown in the preceding figures.

FIG. 6 is a view similar to FIG. 1 but illustrating a different embodiment of the invention in which relatively small and large animal-simulating bodies are mounted upon spring means in side by side relationship, the same being suspended upon a platform directly supported by downwardly extending elongated members to provide swinging support for the platform to which the animal-simulating bodies are connected.

FIG. 7 is a vertical sectional elevation of one of the animal-simulating bodies and its supporting means as seen on the line 7-7 of FIG. 6.

FIG. 8 is a side elevation of the animal-simulating body of the exemplary type shown in FIG. 7 and illustrating one position of the body in full lines with respect to the supporting platform while resting upon a horizontal surface such as a floor, and in phantom, showing a limited tilting, swinging or bouncing type movement of the body relative to the platform and illustrating the movement limiting function of the foot rest bar which extends through said body.

FIG. 9 is a fragmentary side elevation of another embodiment of stabilizing means for the transverse supporting members which extend through the body of the riding toy for purposes of preventing relative rotation between said bar and body and thus rendering the toy safe to use.

FIGS. 10-13 are views similar to FIGS. 4 and 5 but respectively showing additional spring arrangements to support a body of a riding type toy to produce different bouncing movements.

DETAILED DESCRIPTION

Referring to FIGS. 1-3, it will be seen that a substantially rectangular platform 10 is mounted upon an intermediate supporting frame 12 which is suspended by a plurality of elongated members 14 which are mounted adjacent a pair of transversely spaced upright members 16. The lower ends of opposite pairs of said elongated members 14 are connected by transversely extending connecting members or portions 18, whereby each pair of members 14 and the connecting

member 18 thereof comprise a substantially U-shaped torsion bar of the type shown and described in applicants prior U.S. Pat. No. 3,648,307, issued Mar. 14, 1972 and his even earlier U.S. Pat. No. 2,459,423, to which attention is directed for further details. In essence, the torsion bars are of such nature as to prevent any substantial movement, for example, of the transverse portions 18 thereof in an axial direction. The upper ends of the elongated members, which comprise legs of said U-shaped torsion bars, respectively are bent outwardly for reception within suitable bearings 20 preferably recessed within the inner surfaces of the upright members 16.

The upright members 16 are also secured preferably in vertical position perpendicular to a floor or other supporting surface by being secured to the opposite ends of a horizontal rectangular frame or enclosure 22 within which, for example, an elongated coiled spring type motor 24 is contained. The motor is energized, for example, by a crank 26 shown at the right hand end of FIG. 1. The spring motor 24 is suitably connected to a rocking lever 28 which is parallel to and adjacent the inner surface of one of said upright members 16, as seen at the left hand end of FIG. 1, the rocking lever being mounted for oscillation through a limited arc in the manner indicated by the directional arrows shown in FIG. 2. The upper end of the lever 28 is provided with a slot 30 within which a pin 32 is disposed. The pin projects outwardly from the outer surface of an upstanding member 34 which is connected to one end of the platform 10 and preferably is braced by a suitable block 36, for example, or otherwise.

As best seen from FIGS. 2 and 3, the intermediate supporting frame 12 is substantially U-shaped in cross-section for purposes of accommodating the frame 22 which encloses the coiled spring motor 24. This results in the frame 12 having downwardly extending legs 38 at opposite corners thereof and preferably anti-friction bearings 40 are suitably recessed into said legs and the opposite end portions of the transverse members 18 of the U-shaped torsion bars extend therethrough. Suitable staking means, or otherwise, are utilized to position the bearings longitudinally with respect to the transverse members 18 and thereby secure the intermediate supporting frame 12 in longitudinally desired relationship with respect to the upwardly extending elongated members 14 which project from opposite ends of the members 18. Thus, in swinging movement of the intermediate supporting frame 12 with respect to the upright members 16, no interference is encountered but if desired, appropriate guide means may be provided on the inner surfaces of upright members 16, for example, for engagement by the outer surfaces of the opposite ends of intermediate supporting frame 12, if desired, such guide means being of a stabilizing type such as those shown in either of applicants previously mentioned U.S. patents.

The outer sides of the intermediate supporting frame 12 preferably are covered by suitable panels 42, for example, which extend between and are connected to the outer surfaces of the legs 38, thereby somewhat masking the box-like enclosure frame 22 for the motor 24. Further, the box-like frame 22 also serves as stop means for limiting the swinging movement of the intermediate supporting frame 12 as suspended upon the members 14.

The platform 10 may be formed from any suitable material such as plywood, of suitable thickness, such as of the order $\frac{1}{2}$ inch, for example. The platform preferably is readily detachably connected to the upper surfaces of the various elements comprising intermediate supporting frame 12 by quick-detachable means comprising, for example, angularly extending pins 44 which are fixedly supported by opposite end elements of the frame 12, as best shown in FIG. 3, the same extending through complementary angular openings formed in the opposite ends of the platform 10 adjacent one side edge thereof. The opposite side edge of platform 10 is provided with openings which receive the upper ends of bolts 46, the lower portions of which are firmly connected to opposite end portions of the supporting frame 12 and the upper end portions extend through appropriate complementary openings formed in the platform 10, wingnuts 48 preferably being used to prevent accidental removal of the platform 10 from the supporting frame 12 until such removal is desired. The lower surface of the platform 10 also preferably is smooth, so that the same may be disposed upon a supporting surface such as a floor, for example, if no rocking movement of the animal-simulating bodies mounted thereon is desired. Such bodies and the connection thereof to the platform 10 now will be described.

Especially for purposes of affording enjoyment to children, the platform 10 is intended to support animal-simulating bodies, such as a suitably molded body of a horse 50; any other shape of animal may be used, as desired, whereby the illustrated horse is merely intended to be exemplary. Said body may be suitably molded from synthetic resin, for example, and types of horses of this kind are readily available from manufacturers. They can be obtained in different sizes. Similarly, if desired, as shown in FIGS. 1 and 2, a suitable seat-like object 52, having opposite sides 54 which respectively imitate the opposite sides of an animal such as a horse may be mounted upon the platform 10, the object 52 having a seat 56 extending between the side members 54. Also a foot bar 58 and a hand bar 60 are disposed between the side members 54 appropriately. The object 52 preferably is for very young children who may sit therein upon seat 56 in substantial safety.

The animal body 50, such as a horse, may be provided with a pair of bars 62 which extend transversely through appropriate openings in the body respectively adjacent opposite ends thereof. This is best illustrated in FIG. 3. The body 50 also has a seat 64 thereon, which simulates a saddle for example. Further, a hand bar 66 extends through and projects beyond opposite sides of the head portion of the body 50, while a foot-engageable and supporting bar 68 extends through and projects at opposite sides outwardly from the forward portion of the body 50, such as from the forwardly extending front leg portion, as clearly shown in FIG. 3.

The body 50 is supported with respect to the platform 10 by spring means, several examples of which respectively are shown in FIGS. 4 and 5 as well as in FIG. 3. It will be seen that the spring means 70 shown in FIG. 3, for example, have oppositely bowed portions 72 and 74 which are integrally connected and the lower ends of the bowed portions 72 also are integrally connected by an intermediate portion 76 which rests flatly upon the platform 10 and is fixedly secured thereto by appropriate bolts or otherwise. The upper ends of the upper

bowed portions 74 respectively extend outwardly from each other and are securely connected by bolts or otherwise to the oppositely projecting portions of the transverse bars 62 which project through the body 50.

In order to prevent undue bouncing gyration of the body relative to the platform 10 when an active child is seated upon the body 50, it has been found that a safe situation can be achieved, while permitting limited vertical bouncing movement, by rendering the bars 62 substantially non-rotatable with respect to the body 50. One embodiment for accomplishing this is illustrated in FIGS. 3-5, in which it will be seen that U-shaped bars 78 extend horizontally above the platform 10 and the opposite ends thereof extend upwardly through the bars 62 and are appropriately connected thereto by appropriate nuts, for example, affixed to threads on the terminal ends of the U-shaped bar 78. Such arrangement is effective, yet is relatively inexpensive. Under certain circumstances, the bars 78 and especially the horizontal lower portions thereof may serve somewhat as a form of stirrup, as well as means to assist a child in mounting the seat 64 of the body 50, especially in regard to small, younger children.

The shapes of the springs 70 shown in FIG. 3 may be varied in different ways. For example, in FIG. 4, it will be seen that the springs 70' are separate but each have oppositely extending bowed portions 72' and 74', but the lower ends of the portions 72' are not connected but instead, are separately connected by appropriate bolts or screws to the platform 10.

The arrangement in FIG. 5 is similar to that shown in FIG. 4 except that the separate springs 70'' are reversed with respect to each other as compared with the arrangement in FIG. 4, while the connected bowed portions 72'' and 74'' are provided for desirable functioning as in regard to the spring arrangement shown in FIGS. 3 and 4. The bars 62 to which the upper ends of the U-shaped stabilizing bars 78 are connected render the bars 62 substantially non-rotatable with respect to the body 50 when mounted thereon, no such body being shown in the illustration of FIGS. 4 and 5 in order to simplify the views.

Referring to FIGS. 6 and 7, it will be seen that the platform 10 is mounted at a lower level with respect to a supporting surface such as floor 80. This is accomplished by providing a pair of cross members or battens 82 which are fixedly connected beneath the opposite ends of the platform 10, by any suitable means such as bolts, weldments or otherwise. Referring to FIG. 7, it will be seen that the battens 82 have bearings 84 recessed therein at longitudinally spaced positions for reception of the intermediate portions 18 of the preferably U-shaped torsion bars which include the vertically extending elongated members 14, the upper ends of which are pivotally supported within recessed bearings 20 provided in the upright members 16, as in the embodiment illustrated in FIG. 1.

The embodiment shown in FIGS. 6 and 7 has no motor or oscillating bar to effect swinging movement of the platform 10 with respect to upright members 16. Also, the members 16 are connected together adjacent the lower ends thereof by a transverse beam or panel 86 which is of rugged nature and employs stout angles or brackets 88 which are rigidly connected respectively to the members 16 and beam or panel 86 by heavy duty means such as screws, bolts or otherwise. Said support-

ing means which permits the platform 10 to be mounted closer to the floor 80, for example, disposes the bodies 50 and 50' closer to the floor and thereby even further minimizes the possibility of accidents occurring. Further, it will be seen that the body 50' is smaller than the body 50 and is adapted to support a smaller or younger child than that for which the body 50 is intended.

As shown in FIGS. 7 and 8, the body 50 is supported by suitable spring means such as spring 70 of the type shown in FIG. 3, such illustration being for exemplary purposes however, rather than restriction. The lower portions of the springs are firmly secured to the platform 10 and, preferably, rubber grommets 90 are disposed between the springs and the platform 10 to provide limited yieldability and thereby enhance the springing action of the springs 70 and facilitate the yieldability of various portions of the springs. It also will be understood that any of the other spring arrangements such as shown in FIGS. 4 and 5, as well as still others, may be substituted for those specifically illustrated in FIGS. 6-8. Otherwise, the function of the springs and the manner in which they are connected with respect to the body 50, so as to prevent relative rotation between the transverse supporting bar 62 and the bodies 50, in the means by which this is accomplished, are the same as shown and described above with respect to the embodiment shown in FIGS. 1-5 and repetition of the same here is not believed to be necessary except to indicate that in FIG. 7, for example, the exemplary curved arrow 92 is included to exemplify the swinging movement provided by the pivoted elongated members 14, which is substantially in opposite horizontal directions, while curved arrow 94 is illustrative of the rocking movement afforded by the springs 70, for example, which is substantially in a vertical direction.

Another feature of the invention is illustrated in FIG. 8 by comparing the two positions of the body 50 wherein, the position shown in full lines is the substantially normal, horizontal position, in which the foot supporting bar 68 is spaced from the right hand end of spring 70, while in the downward position, shown in phantom, the bar 68 engages the springs 70 and thereby limits the forward, downward movement of the body 50 relative to the platform 10, thereby further affording relative safety in operation of the toy.

In addition to the employment of the U-shaped bars 78 to prevent relative rotation between the bars 62 and the bodies 50, attention is directed to FIG. 9 in which another embodiment of transverse bar 62 is shown in sectioned vertical view, the same extending through an opening 96 in body 50 which is complementary to the cross-sectional shape of the polygonal transverse bar 62' and thereby prevents relative rotation between said transverse bar and the body. Any of a number of suitable alternative geometric shapes may be used within the spirit of the invention. This construction may be used in lieu of the U-shaped bars 78 shown in the preceding figures, for example, where the latter are not desired.

The spring arrangements shown in FIGS. 3, 4 and 5 are exemplary of several types of spring mountings which may be used to produce the bouncing movements of various types described above. However, other arrangements of the springs are possible to produce variations in movements which primarily are in an

up and down direction, including some pivotal or swivel type motions. Examples of such other arrangements are shown in FIGS. 10 and 11 wherein, in the arrangement of FIG. 10, there will be a tendency for the front end of the body 50, of the preceding figures, to move farther downward than the rearward end thereof, while in the arrangement of FIG. 11, the opposite is the case, due to the particular arrangements of the springs 70 in fore and aft relation of the lower bowed portions 72 in particular, which are responsible for permitting the greatest amount of vertical movement, as compared to bowed portions 74 of said springs.

In FIGS. 12 and 13, a different resulting movement of the supported body is possible, of a somewhat gyrating motion. This is due to arranging both the springs 70 at one side of the body in a reverse position to the springs on the opposite side of the body. Thus, in FIG. 12, the larger bowed portions 72R at the right side of the body 50 both extend rearwardly, as shown in FIG. 10, and the larger bowed portions 72L of the springs at the left side of body 50 extend forwardly, as shown in FIG. 11. In FIG. 13, the larger bowed portions 72R at the right side of body 50 are arranged like the springs 70' shown in FIG. 4 while at the left side of the body 50, the larger bowed portions 72L are arranged as shown in FIG. 5.

From the foregoing, it will be seen that the present invention provides an animal type riding toy for children which uses simulated animal bodies supported by spring means which afford bouncing movement in a more or less vertical direction, while the platform upon which the bodies are supported are connected to the lower end portions of preferably U-shaped torsion bars which include vertically disposed elongated members 14 which provide swinging movement for the platform 10 and the bodies 50 supported thereby, the members 14 preferably being substantially parallel to each other so that the platform 10 is substantially horizontal in all swinging positions. As a result, compound movement of the bodies 50 is provided to afford enjoyment to children and simulate not only up and down vertical movement of a real horse but also rearward and forward movements thereof when the bodies 50 are at least in opposite horizontal directions during the excursions of the platform 10 as supported by the torsion bars.

While the invention has been described and illustrated in its several preferred embodiments, it should be understood that the invention is not to be limited to the precise details herein illustrated and described since the same may be carried out in other ways falling within the scope of the invention as illustrated and described. In particular, the illustrated animal simulating bodies are exemplary of a substantial range of riding toys which may be employed, such as automobiles, fire trucks, aeroplanes, rockets, and otherwise.

I claim:

1. A riding type toy for children comprising in combination, a substantially horizontal platform, a simulated body having a seat means to accommodate a child mounted in spaced relation to said platform above the upper surface thereof, spring means extending between said platform and the lower portion of said body to constitute the sole connection therebetween and operable to permit vertical springing and swivel movement of said body relative to said platform, a frame having a pair of transversely spaced upright members respectively adjacent a pair of opposite side edges of said plat-

form, elongated members extending downwardly from the upper portions of said upright members and depending therefrom for swinging movement of the lower portions thereof, and means interconnecting the lower portions of said suspended members to said platform at transversely spaced locations in opposite substantially horizontal directions, whereby compound swinging and springing movements of said body relative to said frame are induced by actions of the rider and are indirectly compounded by the swinging movement of the platform.

2. The toy according to claim 1 in which pairs of said elongated members extend downward from the upper portions of said upright members at transversely spaced locations with respect to said upright members to effect movement of said platform and the body connected thereto substantially within a horizontal position at various elevations controlled by the swinging movement of said elongated members.

3. The toy according to claim 1 in which said spring means comprise multiple sections bowed outwardly in reverse directions and respectively engage said body adjacent opposite ends thereof to permit tilting vertical springing movements thereof when a child is supported upon said body.

4. The toy according to claim 3 in which said spring means extend within vertical planes and the lower portions of said spring means are fixed to said platform and the upper portions thereof are secured to members extending transversely through said body respectively adjacent opposite ends thereof and fixed non-rotatably to said body, the opposite ends of said transverse members projecting from opposite sides of said body for connection to the upper portions of said spring means.

5. The toy according to claim 4 further including a foot rest bar projecting through the forward portion of

said body and normally spaced at a predetermined distance above said spring means and the opposite end portions of said foot rest bar being adapted to engage areas of said spring means incident to tilting movement of said body relative to said platform and thereby limit downward movement of said body toward said platform for purposes of safety.

6. The toy according to claim 4 in which said spring means are provided with S-shaped portions respectively facing in opposite direction and the lower ends thereof being connected by an integral member comprising portions of said spring means.

7. The toy according to claim 1 further including an intermediate supporting frame between the lower portions of said elongated members and said platform, motor means positioned beneath said platform, and a rocking arm pivoted relative to one of said upright members and interconnected to said motor for oscillating movement thereby, said rocking arm also intervening said platform and being adapted to move it horizontally for swinging movement to and fro.

8. The toy according to claim 7 in which said intermediate supporting frame is substantially U-shaped in cross-section and straddles said elongated motor means, said motor means extending between said upright members and including spacing means connected at the ends thereof respectively to the lower end portions of said upright members.

9. The toy according to claim 8 in which said platform is provided with an upstanding member connected to one end thereof, and pin and slot co-engaging means disposed between the upper portion of said upstanding member and said rocking arm to provide an oscillating movement of said arm reciprocation of said platform in opposite substantially horizontal directions in a gliding motion.
